(57) **CLAIM**

The ornamental design for an LED lamp, as shown and described.

DESCRIPTION

FIG. 1 is a perspective view of a first embodiment of an LED lamp showing our new design;

FIG. 2 is a perspective view of a second embodiment of the LED lamp;

FIG. 3 is a perspective view of a third embodiment of the LED lamp;

FIG. 4 is a top plan view of the third embodiment, and the claimed portions shown in this view are identical to those of the first and second embodiments;

FIG. 5 is a bottom plan view of the third embodiment, and the claimed portions shown in this view are identical to those of the first and second embodiments;

FIG. 6 is a front side elevational view of the third embodiment, wherein the front side is at the bottom of the FIG. 4 view, and the claimed portions shown in this view are identical to those of the first and second embodiments except for differences in size;

FIG. 7 is a back side elevational view of the third embodiment, and the claimed portions shown in this view are identical to those of the first and second embodiments except for differences in size;

FIG. 8 is a left side elevational view of the third embodiment, and the claimed portions shown in this view are identical to those of the first and second embodiments except for differences in size; and,

FIG. 9 is a right side elevational view of the third embodiment, and the claimed portions shown in this view are identical to those of the first and second embodiments except for differences in size.

The broken line showing of certain portions of the LED lamp is included for the purpose of illustrating only and forms no part of the claimed design.
